UNITED STATES PATENT OFFICE

170,534

KNIFE SHARPENER

Arthur Eugene Johnson and Irene Walls Johnson,
Los Angeles, Calif.

Application January 9, 1953, Serial No. 23,091

Term of patent 14 years

(Cl. D37—1)

To all whom it may concern:

Be it known that we, Arthur Eugene Johnson and Irene Walls Johnson, citizens of the United States residing at 7039½ Freeman Blvd., in the county of Los Angeles and State of California, have invented a new, original, and ornamental Design for a Knife Sharpener, of which the following is a specification, reference being had to the accompanying drawing, forming a part hereof.

Fig. 1 is a side elevational view of a knife sharpener embodying our new design;

Fig. 2 is a front elevation thereof;

Fig. 3 is a rear elevation thereof;

Fig. 4 is a bottom plan view thereof;
Fig. 5 is a section on line 5—5 of Fig. 1; and
Fig. 6 is a section on line 6—6 of Fig. 1.

We claim:

The ornamental design for a knife sharpener, as shown.

ARTHUR EUGENE JOHNSON.
IRENE WALLS JOHNSON.
